UNITED STATES PATENT OFFICE.

GEORGE H. FOUNTAIN, OF PLAINFIELD, NEW JERSEY.

SIFTER.

SPECIFICATION forming part of Letters Patent No. 399,862, dated March 19, 1889.

Application filed July 31, 1888. Serial No. 281,518. (No model.)

To all whom it may concern:

Be it known that I, GEORGE H. FOUNTAIN, of Plainfield, in the county of Union and State of New Jersey, have invented a new and 5 Improved Sifter, of which the following is a full, clear, and exact description.

My invention relates to an improvement in sifters, and has for its object to provide a sifter of simple, durable, economical, and convenient construction; and a further object of the invention is to provide a sifter with a perforated or reticulated drum having an automatically-closing door; and the further object of the said invention is to provide a sifter 15 with means whereby a chute or slide may be expeditiously constructed to carry off the sifted products when desired.

My invention consists in certain novel features of construction and peculiar combination of parts, as will be hereinafter fully described, and particularly pointed out in the claims.

Reference is to be had to the accompanying drawings, forming a part of this specification, 25 in which similar figures of reference indicate corresponding parts in all the views.

Figure 1 is a perspective view of the sifter, illustrating one side as partly broken away and the slide or chute constructed in the same. 30 Fig. 2 is a central vertical section of the sifter in position for operation. Fig. 3 is a perspective view of the drum. Fig. 4 is a side elevation of the drum-spindle; and Fig. 5 is a vertical section of the sifter, taken on the 35 line 5 5, Fig. 1.

In carrying out the invention the frame 10 of the sifter is preferably rectangular in contour and provided with a hinged or detachable top, 11. In the front side of the frame 40 below the center a door, 12, is hinged adapted to open inward, which door is of a width essentially equal to the width of the said front side. When the door is closed, it is secured by a button or catch of any approved form; 45 or the said button and catch may be dispensed with and the door be held closed by friction only. When the said door is open or folded inward, it is held at an upward inclination through the medium of a block, 13, attached 50 to the inner sides of the frame, as best illustrated in Fig. 1.

In the rear side of the frame, or that side opposite to the one to which the door 12 is hinged, a second door, 14, is provided, of equal width with the door 12, the said door 14 being 55 hinged at the upper edge, while the door 12 is hinged at the lower edge. The purpose of this construction is, by the connection of the two doors, to provide a slide or chute bridging the frame at or about the center, which is 60 accomplished by opening the door 12 inward, as aforesaid, and then carrying the rear door, 14, also inward to a contact with the under surface of the door 12. By pressing upward upon the door 14 the door 12 is raised from 65 the block 13 and the door 14 permitted to pass above the said door 12, whereupon the rear door, 14, is permitted to fall and rest upon the inner edge of the forward door, as best illustrated in Fig. 1. Thus a slide or 70 chute is provided having an inclination from the rear to the forward side of the frame, the door 12 being supported upon the block and the door 14 upon the said door 12.

The drum 15 is preferably made rectangular 75 in cross-section, consisting of two ends, 16, and sides of perforated or reticulated material—such as woven wire—the said perforated or reticulated material being securely fastened to the sides in any suitable or approved 80 manner. One side of the drum is provided with an opening extending entirely across said side, which is closed by a lid, 17, constructed of a material similar to that constituting the sides of the drum. The said lid 17 85 is provided with a longitudinal rod at its outer end, the ends of which are pivoted in the ends 16 16 of the drum, as best shown in Figs. 3 and 5. By reason of the lid 17 being pivoted in the drum, as aforesaid, when the 90 side containing the opening covered by said lid is brought uppermost, when said drum is revolved in the direction shown by arrow, Fig. 5, the lid will assume a perpendicular position, exposing said opening, so that the material to be sifted may be readily placed in the drum. When, however, the said lidded side of the drum is brought to a perpendicular 95 position, the lid will automatically fall down, assuming an equivalent position, thereby closing the opening and preventing the 100 egress of the material.

The lid 17 is preferably made of less length than the length of the drum, and in order that the material to be sifted—cinders, for instance—may not clog the lid by filling the 5 space intervening the ends of the same and the ends of the drum a shield, 18, is attached to the edge of the ends 16 of the drum, adjacent to the side containing the lid, which shield is adapted to project beyond the inner 10 face of the ends 16, and consists, preferably, of a strap of metal, as best shown in Fig. 3.

In the ends of the drum 15 aligning rectangular apertures 18^a are produced, which apertures are adapted to receive a rectangular 15 spindle, 19, which spindle, passing longitudinally through the drum, is made to extend outward from either end and into rectangular apertures 20, formed in opposite sides of the sifter-frame, as best shown in Fig. 1.

20 In order that the drum when journaled in the sifter-frame may be revolved, the surface of the spindle 19 adjacent to the ends is concaved at 21, as best shown in Fig. 4. When it is desired to revolve the drum for the purpose of sifting, the spindle 19, which is provided with a suitable crank, 22, is pushed back or pulled forward, as the case may be, until the cylindrical or concaved surface 21 25 of the spindle is brought to a bearing in the frame of the sifter, as illustrated in Fig. 2. When it is intended to locate the drum to receive the material to be sifted, the spindle is pushed inward or drawn outward until the rectangular portion thereof has entered the 30 rectangular openings or apertures 20 in the frame.

In operation, the rectangular portion of the spindle being entered in the apertures 20 of the frame and that side of the drum having 35 the lid being uppermost, the top 11 of the sifter-frame is removed and the material to be sifted placed in the drum. The spindle is now slid endwise and turned so as to bring the same into the position shown in Fig. 2. 40 The drum or sieve proper is then revolved (through the medium of the crank 22) in the direction shown by the arrow, Fig. 5. As the

drum is turned, the lid will fall to close the feed-opening in the said drum, as shown by the dotted lines in Fig. 5, and will be held 50 closed by the contents of the sieve. When the contents of the said drum shall have been properly sifted, the doors 12 and 14 are brought down to the position illustrated in Fig. 1, forming a slide or chute to discharge the 55 sifted material, when emptied thereon, to the outside of the frame. The drum is then revolved in the opposite direction until the lid 17 uncovers the opening. The sifted material will then pass out of the drum onto the 60 chute or slide, as will be readily understood from the drawings.

Having thus described my invention, what I claim as new, and desire to secure by Letters Patent, is—

65 1. The combination, with a drum adapted to be rotated and a door pivoted in said drum opening inward, of a shield extending from the sides of the drum inward over the door-opening, substantially as described, whereby 70 material within the drum is prevented from clogging the door, as set forth.

2. The combination, with the sifter-frame and a drum provided with a door pivoted in one side opening inward and closing by gravity, 75 said door adapted to be held closed by the material when the drum is turned in one direction and to swing inward and open the feed-opening when turned in the opposite direction, of a door hinged near the lower front 80 end of the sifter-frame, a similar door hinged near the upper rear end of the frame, and inclined blocks or stops attached to the inner wall of said frame, said doors adapted to swing inward and said front door adapted to engage 85 the blocks and the rear door to engage the inner upper end of the front door when opened inward, thereby forming a chute or slide, substantially as and for the purposes specified.

GEORGE H. FOUNTAIN.
